UNITED STATES PATENT OFFICE.

GEORG KARL VILHELM JOHANSON, OF STOCKHOLM, SWEDEN.

COIN-CONTROLLED VENDING APPARATUS.

1,354,653.

Specification of Letters Patent.

Patented Oct. 5, 1920.

Application filed June 6, 1919. Serial No. 302,158.

To all whom it may concern:

Be it known that I, GEORG KARL VILHELM JOHANSON, a subject of the King of Sweden, residing at Stockholm, in the Kingdom of Sweden, have invented a new and useful Improvement in Coin-Controlled Vending Apparatus, of which the following is a specification.

The present invention relates to a coin controlled vending apparatus for meters for gas, water, and other fluids, and has for its purpose to provide an apparatus of the said kind which shall be as simple and inexpensive as possible and yet operate in a perfectly reliable manner. The invention relates to that kind of such apparatus which are provided at the lower end of a coin chute, with a movable member connected with the delivery valve for the fluid, which member is adapted to be operated through the medium of a coin introduced into the chute by a second member located opposite said first-named member and adapted to be operated from the outside of the apparatus so as to open said valve, and which are provided below the coin chute with a rotatable disk connected with the meter, said disk being provided with a pocket for receiving the coin.

30 The present invention is characterized by this that said disk is rigidly connected with a cam disk provided at its circumference with a notch engaged by a lug on the member connected with the delivery valve, when 35 said valve is closed, and that the pocket in the firstmentioned disk has such oblique shape and is so positioned relatively to said notch, that when said lug engages said notch, said pocket is retained in a slightly 40 oblique position below the coin chute, so that when said firstnamed member is actuated by said second member through the medium of the coin for opening the valve, the coin will be pressed downward into the 45 pocket and thus positively brought along during the rotation of the disk.

One embodiment of the invention is illustrated in the accompanying drawing in which Figures 1, 2, and 3 show the apparatus 50 with its parts in different positions.

In the construction illustrated, 1 denotes the coin chute which is open in front, or covered by a transparent pane or covering, so that it is possible to ascertain from the 55 outside whether there are any coins in said chute. 2 denotes a member rotatable on the

stud 3 and connected with the delivery valve for the gas in such manner that said valve is maintained closed when the member 2 occupies the position illustrated in Figs. 1 and 2, 60 but is open when said member is turned into the position illustrated in Fig. 3. Opposite the member 2 there is located another member 4 rotatable on the stud 5, said member 4 serving through the medium of a projection 40 and a coin 6 put into the coin chute to move the member 2 from the position illustrated in Figs. 1 and 2 to the position shown in Fig. 3. For this purpose said member 4 is provided with an operating arm 7 projecting outside the casing inclosing the apparatus, which casing is not shown in the drawing. A disk 8 is rotatably journaled beneath the coin chute 1, said disk being driven by the meter in any convenient manner, and being provided with a pocket 9 adapted to receive the coin 6 from the coin chute 1. The members 2 and 4 are located on either side of the coin chute, the projection 40 on the member 4 projecting beneath 70 the coin chute into the pocket 9 in the disk 8, when in the position shown in Fig. 1 before the apparatus is operated, thereby preventing the coins from dropping into said pocket. The disk 8 is rigidly connected to a cam 75 disk 10 which is provided with a deep notch 17 into which a lug 16 on the member 2 may snap, being actuated by a spring, when the disk has been turned one revolution, thereby causing the delivery valve for the gas to 80 close, provided that in the meantime no further coin has dropped into the pocket 9 and prevents, by engagement with the projection 21 on the member 2, the lug 16 on said member from snapping into said notch. During 85 the movement of the disk 8 said disk obstructs the path of the projection 40, which may be turned inward only when the disk 8 occupies such position that the pocket 9 is in its uppermost position, provided that no 90 further coin has previously dropped into the pocket in which case such further coin prevents the member 4 from being turned inward. The movement outward of the member 4 while the disk 8 is rotating will have 100 no effect whatsoever on the operation of the apparatus. The member 2 is returned to initial position by means of a spring or the like tending to turn said member 2 in the direction to the right in the drawing. 110

As will be seen from Figs. 1 and 2, the pocket 9 in the disk 8 has such oblique shape

and is so positioned relatively to the notch 17 in the cam disk 10 rigidly connected with the disk 8, that when the lug 16 engages the notch 17, the pocket 9 is retained in a slightly oblique position below the coin chute, so that when the member 2 is actuated by the member 4 through the medium of the coin 6, said coin will be pressed downward into the pocket 9 so that it will be positively brought along during the rotation of the disk 8.

The apparatus above described operates in the following manner:

When a coin has been put into the chute

- 15 1 through the upper opening 15 the member 4 is moved outward by means of the arm 7 so that the coin 6 may drop past the projection 40 into the mouth of the pocket 9 and occupy a position intermediate the projection 40 on the member 4 and the projection 21 on the member 2, as shown in Fig. 2. When the member 4 is again moved inward the member 2 is moved to the left through the medium of the coin 6, so that 25 the lug 16 is lifted out of the notch 17, and the delivery valve for the gas is opened. Simultaneously, the coin is forced to the bottom of the pocket 9, in which position it maintains the member 2 in its position to 30 the left, so that the gas valve remains open, as long as there is no consumption of gas so that the disk 8 will remain stationary. If gas is consumed the disk 8 will be able 35 to rotate in the direction indicated by the arrows, on account of the lug 16 being out of engagement with the notch 17. During the rotation the disk 8 will bring along the coin 6 in the pocket, and when said coin has passed the projection 40 it may drop into a 40 coin receptacle, the lug 16 on the member 2 bearing against the periphery of the disk 10 maintaining the gas valve open. When the disk has been turned one revolution, however, the lug 16 will again snap into the 45 notch 17, if a new coin has not dropped into the pocket thereby preventing said snapping movement. When the lug 16 snaps into the notch 17 the delivery of the gas will be interrupted, causing the meter to stop. The

various members of the apparatus now occupy the positions shown in Fig. 1. When another coin is put in, the same operation will be repeated.

It is suitable to provide the casing of the apparatus with a window rendering it possible to ascertain if there are any coins in the coin chute. It will be understood that it is possible to fill the entire coin chute at once with coins, said coins dropping one by one into the pocket as the gas is consumed, without the arm 7 having to be operated for each coin.

I claim:

In a coin controlled vending apparatus for meters for gas, water, or other fluids, the combination of a coin chute, a member at the lower end of said coin chute adapted to be operated from the outside of the apparatus, a second member connected with the delivery valve for the fluid and located at the lower end of said coin chute opposite said first named member in such manner as to be operated by said first named member through the medium of a coin in the coin chute so as to open said valve, a lug on said second member, a cam disk at the lower end of said coin chute provided at its circumference with a notch adapted to be engaged by said lug on said second member connected with the delivery valve when said valve is closed, and a rotatable disk rigidly connected with said cam disk and connected with the meter and located below said coin chute, said disk being provided with a pocket for receiving a coin having such oblique shape and so positioned relatively to said notch in said cam disk that when said lug engages said notch said pocket is retained in a slightly oblique position below the coin chute, so that when said second member is actuated by said first named member through the medium of the coin for opening the valve, the coin will be pressed downward into the pocket and thus positively brought along during the rotation of said disk.

GEORG KARL VILHELM JOHANSON.
